UNITED STATES PATENT OFFICE

KARL HERRMANN, OF VIENNA, AUSTRIA, ASSIGNOR, BY MESNE ASSIGNMENTS, TO
BONICOT CORPORATION OF AMERICA

PROCESS OF RENDERING NONPOISONOUS THE TOBACCO FUMES DURING SMOKING

Application filed June 17, 1930, Serial No. 461,827, and in Austria February 15, 1930.

This invention relates to a process of absorbing the tobacco-fumes saturated with nicotine, pyridine and ammonia.

It is already known to deprive of poison 5 the noxious ingredients of the tobacco-fumes by means of certain ferric salts in that ferric chloride or ferric ammonium sulphate is introduced either into the tobacco or into a filter arranged in front of the cigar or the cigarette for instance in the mouthpiece. It is also known to admix absorbents to the tobacco, for instance infusorial earth or the like, in order to hold back the unpleasant tasting empyreumatic oil.

10 According to the present invention neither the tobacco is prepared before the cigarette or cigar is made, nor are insertions arranged in the cigarette or cigar, but the finished cigarette or cigar is treated in such a way as to render harmless the nicotine or nonpoisonous 15 ingredients by injecting a liquid into the tobacco some distance away from the end of the cigarette or cigar, whereby the smoke is rendered nonpoisonous by the chemical reaction.

20 In carrying out the present invention the liquid is injected into the tobacco and the tobacco itself carries the ferric salts.

The liquid drop, injected into the tobacco by means of a syringe or the like, is located 25 some distance away from the forward end of the cigarette or cigar, while in a like way a liquid drop containing ferric salts is injected into the tobacco from the rear end of the cigarette or the like. The salts firmly adhere 30 to the tobacco and on the drawn-in smoke.

The action is as follows:—

Besides the important fact that the appearance of cigarettes is not changed in any way by wetting an end thereof, the drop located 40 in the tobacco some distance away from the forward end partially reduces the poisonous substances contained in the smoke drawn off, in view of the moisture distributed over the entire cigarette or cigar.

45 The smoke, partially rendered nonpoison-

ous, now passes through the upper zone in which the ferric salts and acids are effective, so that the smoke drawn into the mouth is freed of the greatest part (about 80%) of the nicotine, pyridine and ammonia and practically of the entire empyreumatic oil, without appreciably influencing the aroma and taste. All noxious substances are accumulated in the remaining part or rest of the tobacco which is thrown away.

50 By suitable dosing the quantity of the injected liquid or by injecting the liquid at one end only, the smoker can readily suit to his taste the extent of rendering harmless the poisonous substances.

55 Of course also pipe-tobacco can be treated in a similar way by suitably injecting the liquid into the filling of the pipe.

60 A solution of tartaric acid, citric acid and sodium chloride to which are added ferrous ammonium sulphate (Mohr's salt) and finally coumarin dissolved in alcohol, and if desired also scents, has been found to be a particularly favorable injection-liquid. Although 65 generally it may be quite sufficient to inject only a liquid (water) at the forward end of the tobacco, the solution above stated can be used for both injections for the sake of simplicity.

70 Any convenient injector may be used for this purpose. Preferably the pointed forward end of the syringe is solid and lateral discharge openings are arranged above the same, in order to provide for a good distribution and spreading of the liquid drop.

75 In the accompanying sheet of drawing, the figure shows a cigarette partly in section treated according to the present invention.

In the drawing, 1 designates a liquid drop injected at the forward end and 2 a drop of 80 the solution injected at the rear end of the cigarette.

I claim:—

1. Process of rendering nonpoisonous the tobacco smoke during smoking which con- 85

sists in injecting a liquid into the cigar or cigarette at its forward end, and injecting a solution containing a ferric salt into the cigar or cigarette at its rear end.

5 2. Process of rendering nonpoisonous the tobacco smoke during smoking which consists in instilling just before smoking a solution containing a ferric salt into the cigar or cigarette near one end thereof in order to
10 form at this place a moist zone which remains moist during the smoking and thus prevents the passage of poisonous fumes.

In testimony whereof I affix my signature.

KARL HERRMANN.
